UNITED STATES PATENT OFFICE

CHARLES A. SCHALLIS, OF ERNESTVILLE, LINCOLN PARK, NEW JERSEY, ASSIGNOR TO
THOMAS A. EDISON, INCORPORATED, OF WEST ORANGE, NEW JERSEY, A CORPORA-TION OF NEW JERSEY

DESIGN FOR A WAFFLE BAKER OR LIKE ARTICLE

Application filed March 17, 1931. Serial No. 39,116. Term of patent 14 years.

To all whom it may concern:

Be it known that I, CHARLES A. SCHALLIS, a citizen of the United States, and a resident of Ernestville, Lincoln Park, in the county of Morris and State of New Jersey, have invented a new, original, and ornamental Design for Waffle Baker or Like Article, of which the following is a specification, reference being had to the accompanying drawings, forming a part thereof.

In the drawings:

Fig. 2 is a front elevation of the same.

The dominant feature of my design consists in the general configuration of the pedestal and body portions of the waffle baker, substantially as shown in the drawings.

I claim:

The ornamental design for a waffle baker or like article, substantially as shown and described.

CHARLES A. SCHALLIS.
